[57] CLAIM

The ornamental design for a circuit protector, as shown and described.

DESCRIPTION

FIG. 1 is a front and upper right perspective view of a circuit protector showing our new design with the actuator in the ON position;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof;

FIG. 7 is a left side elevational view thereof;

FIG. 8 is a cross-sectional view thereof taken along line 8—8 of FIG. 2; and,

FIG. 9 is a cross-sectional view thereof taken along line 8—8 of FIG. 2 showing the actuator in the OFF position.

FIG. 1

FIG. 2

FIG. 3

FIG. 4

FIG. 5

FIG. 6

FIG. 7

FIG. 8

FIG. 9
